US0D1055866S

(12) **United States Design Patent** (10) **Patent No.:** **US D1,055,866 S**
(45) **Date of Patent:** **** Dec. 31, 2024**

(54) **SOCKET**

(71) Applicant: **Guangzhou Leishen Electric Manufacturing Co., Ltd.**, Guangzhou (CN)

(72) Inventor: **Lijin Zhou**, Guangzhou (CN)

(73) Assignee: **Guangzhou Leishen Electric Manufacturing Co., Ltd.**

(**) Term: **15 Years**

(21) Appl. No.: **29/791,109**

(22) Filed: **Dec. 30, 2021**

(51) LOC (14) Cl. **13-03**

(52) U.S. Cl. **USPC D13/137.1**

(58) **Field of Classification Search**

(57) **CLAIM**

The ornamental design for a socket, as shown and described.

DESCRIPTION

FIG. 1 is a first perspective view of a socket showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is a perspective view of an extended state of the socket thereof.

The broken lines shown in the drawings depict portions of the socket in which the design is embodied that form no part of the claimed design.

1 Claim, 9 Drawing Sheets
